DESIGN FOR A CLOTHES HANGER

Herman Powers, Bayonne, N. J.

Application November 19, 1943, Serial No. 111,734

Term of patent 3½ years

(CL. D80—8)

To all whom it may concern:

Be it known that I, Herman Powers, a citizen of the United States, residing in the city of Bayonne, county of Hudson, and State of New Jersey, have invented a new, original, and ornamental Design for a Clothes Hanger, of which the following is a specification, reference being had to the accompanying drawing, forming a part thereof.

In the drawing:

Fig. 1 is a front elevational view of a clothes hanger showing my design; and

Fig. 2 is a top plan view thereof.

I claim:

The ornamental design for a clothes hanger, as shown.

HERMAN POWERS.
